UNITED STATES PATENT OFFICE.

ROBERT LEE BOWMAN, OF KNOXVILLE, TENNESSEE.

CONDUCTOR FOR MINE EXPLOSIVES.

1,395,791.

Specification of Letters Patent.

Patented Nov. 1, 1921.

Application filed January 19, 1921. Serial No. 438,416.

To all whom it may concern:

Be it known that I, ROBERT L. BOWMAN, a citizen of the United States, residing at Knoxville, in the county of Knox and State 5 of Tennessee, have invented a new and useful Conductor for Mine Explosives, of which the following is a specification.

This invention relates to a conductor for use by coal miners and the like for the purpose of directing explosive charges back into the holes that are drilled prior to the blasting operations. Heretofore it has been the practice to deposit the powder by forcing back into the holes shells of paper or 10 similar material containing the explosive charges. The method, which is used at the present time, has been found objectionable because it has been a difficult matter to properly insert a paper shell into the drilled hole 15 without causing it to become distorted before the powder is brought to the inner end of the hole and, consequently, the charges having been improperly placed, the result 20 of the blasts has not been up to the requirements for insuring maximum efficiency.

One of the objects of the invention is to obviate the objections heretofore present and which have been pointed out, by providing a conductor in the form of a container or 30 holder in which the filled shell of proper length is placed, said conductor with its contents being insertible into the hole that has been drilled so as to bring the contents of the conductor at the innermost end of 35 the hole if desired, it being possible then to withdraw the conductor so as to leave the explosive charge intact within the hole, thus insuring the desired result when the charge is exploded.

40 A still further object is to provide a conductor which can be adjusted readily for insertion into holes of different depths and different diameters, and to accommodate explosive charges of different proportions.

45 Another object is to provide a conductor which can be used for placing either a loaded shell or a charge of explosive without the shell.

50 Another object is to provide a device of this character the parts of which can be readily adjusted.

Another object is to provide a conductor which can be utilized as an adjustable mandrel whereby paper shells can be formed of the proper size for use and loaded separate 55 from or in the conductor.

With the foregoing and other objects in view which will appear as the description proceeds, the invention resides in the combination and arrangement of parts and in 60 the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a view partly in side elevation and partly in section of a conductor embodying the present improvements.

Fig. 2 is a section on line 2—2, Fig. 1.

Fig. 3 is a section on line 3—3, Fig. 1.

Fig. 4 is a perspective view of a combined cup and closure to be used with the conductor.

Referring to the figures by characters of reference 1 designates a trough shaped conductor section closed at one end, as indicated at 2 and into which telescopes an oppositely disposed trough shaped section 3 likewise closed at one end as indicated at 4. A central opening 5 is formed in the end wall 80 2 and registers with a slot 6 extending into the end wall 4 from the free end thereof, this opening 5 and slot 6 being designed to receive the tubular stem 7 of the follower 8 adapted to slide within the two sections 1 85 and 3. A knob 9 is detachably connected to the outer end of the stem 7 and by means thereof the plunger or follower 8 can be slid within the sections 1 and 3.

90 A stem 10 is extended through the bottom portion of the section 1 and the top portion of the section 3 and has threads extending from the center to the ends thereof, the threads on one half of the stem being pitched oppositely to the threads on the other half 95 thereof. This stem can be rotated by means of a finger piece 11 on one end thereof and

when turned in one direction will cause the section 3 to move into the section 1 while, when turned in the other direction the said section 3 can be removed from the section 1 and swung about the stem 10. Trough-like extensions 12 can be telescopically connected to each other and to the section 1 so as to permit the use of a trough member of any desired length. Extensions 13 telescoping 10 into each other and into the section 3 can also be provided and thus it will be seen that the container can be adjusted to any desired length so as to correspond with the depth of a hole in which the explosive is to be placed. 15 Likewise by rotating the stem 10 the sections 1 and 3 and the extensions connected thereto can be adjusted radially to correspond approximately with the diameter of the hole. Where a telescopic conductor is 20 employed the stem 7 of the plunger or follower 8 can be made of telescopically connected tubular sections as shown, any suitable means such as bayonet slots 14 and lugs 15 being employed for holding the stem sections 25 properly assembled when extended and rotated, as will be obvious. The removable knob 9 can, if desired, be connected to the end of a rod insertible into the tubular stem 7 and which has been shown at 16, this rod 30 when removed being useful as a ram rod for tamping material within the conductor as hereinafter explained.

A fuse opening 17 is formed in the wall 2 and a slot 18 extends into the follower or 35 plunger 8 adjacent one of its ends.

If desired a graduated cup such as shown at 19 may be employed as a cap or closure for the open end of the conductor when the same is not in use and can also be used as a 40 measure for handling the explosive placed in the conductor.

In using the device herein described the same is first adjusted to the length of the hole in which the explosive charge is to be placed. The stem 10 is then turned so as 45 to move the section 3 and its extensions out of the section 1 and its extensions. The said section 3 and the parts carried thereby are then swung laterally out of position over 50 the section 1 and its extensions. The follower or plunger 8 is then pulled back against the closed end of the section 1, a fuse is inserted through the opening 17 and through the slot 18, and a wad may be placed 55 against the follower or plunger 8. If a paper shell is to be used the same is placed in the section 1 or its extensions and is then filled with the explosive. After the parts have thus been placed the section 3 and its 60 extensions are swung around to position above the section 1 and its extensions. By then rotating the stem 10 the opposed sections are drawn together so as to clamp tightly upon the contents of the follower

and a wad may be then forced into the open 65 end of the conductor. The said conductor is then inserted into the hole so as to project down to the bottom thereof after which the stem 10 is rotated slightly to move the section 3 and its extensions slightly away from 70 the contents of the conductor. The operator holds the stem 7 so as to prevent the plunger or follower 8 from moving and while it is thus held he withdraws the conductor from the hole and from around the explosive 75 charge, leaving said charge within the hole and properly positioned in the desired portion thereof. The charge is then tamped as ordinarily, the fuse being left in the hole and it will be found that in every instance the 80 maximum result will be obtained by placing a charge with the aid of a conductor such as described. The loss of life, property, material, time and labor resulting from the placing of a charge in the old way is entirely 85 eliminated. While a paper shell of the usual or any preferred type can be used in the conductor it is to be understood that a charge of explosive material in loose form can be poured into the conductor and held 90 therein by wads and then inserted into the hole as heretofore described. Also, if desired, a paper shell can be formed by wrapping paper about the conductor, the said conductor being employed as a mandrel. The 95 shell can then be placed inside of the conductor and filled in the manner hereinbefore pointed out.

By providing the slot 18 it is possible readily to disconnect the follower or plunger 100 8 from the fuse immediately after withdrawing the conductor. This is done by giving a slight rotation to the follower or plunger 8 sufficient to cause the slotted portion to move out of engagement with the fuse. 105

What is claimed is:

1. A device of the class described including a charge holding portion adjustable in transverse area, and an ejecting plunger slidable within said portion. 110
2. A device of the class described including a charge holding portion closed at one end and adjustable in transverse area, and an ejecting plunger slidable therein. 115
3. A device of the class described including a charge holding portion adjustable transversely and longitudinally to different areas, and an ejecting plunger movable therein. 120
4. A device of the class described including opposed separable sections constituting charge holding means and an ejecting plunger slidable therein there being a fuse receiving opening in the plunger and in the wall of one of said sections. 125
5. A device of the class described including telescopically connected sections, means for adjusting them toward and from each

other to vary the transverse area therebetween, and an ejecting piston movable between the sections.

6. A device of the class described including coöperating members constituting a transversely adjustable mandrel for shaping a shell and constituting a transversely adjustable conductor for subsequently hold-

ing the shaped shell for insertion into a cavity.

In testimony that I claim the foregoing as my own, I have hereto affixed my signature in the presence of a witness.

ROBERT LEE BOWMAN.

Witness:

Ivy E. SIMPSON.
